(57) **CLAIM**

The ornamental design for the curved bottle opener, as shown and described.

DESCRIPTION

This application relates to Applicant's concurrently filed design application entitled "Bottle Opener", U.S. patent application Ser. No. 29/162,167.

FIG. 1 is a front perspective view of a curved bottle opener according to my design; and,

FIG. 2 is a top plan view of my curved bottle opener of FIG. 1.

The broken line showings in the drawing are for illustrative purposes only and form no part of the claimed design.

The unillustrated views form no part of the claimed design.
